(57) **CLAIM**

The ornamental design for a braid rack, as shown and described.

DESCRIPTION

FIG. 1 is a perspective view of a braid rack.

FIG. 2 is back side elevation view thereof.

FIG. 3 is a front side elevation view thereof.

FIG. 4 is a left side elevation view thereof.

FIG. 5 is a right side elevation view thereof.

FIG. 6 is a top view thereof.

FIG. 7 is a bottom view thereof; and,

FIG. 8 is an enlarged view of portion "8" shown in FIG. 1.

In the drawings, the evenly-spaced broken lines illustrate portions of the braid rack forming no part of the claimed design. The dash-dot broken lines illustrate enlarged view indicators and form no part of the claimed design.

1 Claim, 7 Drawing Sheets
